Attorneys.

UNITED STATES PATENT OFFICE.

LEO G. HAASE, OF LONG BEACH, CALIFORNIA.

DESIGN FOR A BENCH.

Application filed July 20, 1927. Serial No. 22,821. Term of patent 14 years.

To all whom it may concern:

Be it known that I, LEO G. HAASE, a citizen of the United States, residing at Long Beach, in the county of Los Angeles and State of California, have invented a new, original, and ornamental Design for Benches, of which the following is a specification, reference being had to the accompanying drawing, forming part thereof.

The figure is a perspective view of a bench showing my new design.

I claim:

The ornamental design for a bench, as

LEO G. HAASE.
